UNITED STATES PATENT OFFICE.

ALFRED F. MORENCY, OF STURGIS, MICHIGAN, ASSIGNOR TO MORENCY-VAN BUREN MFG. CO., OF STURGIS, MICHIGAN.

BALL-COCK.

1,125,369.

Specification of Letters Patent.

Patented Jan. 19, 1915.

Application filed January 6, 1912. Serial No. 669,805.

To all whom it may concern:

Be it known that I, ALFRED F. MORENCY, citizen of the United States of America, residing at Sturgis, in the county of St. 5 Joseph and State of Michigan, have invented certain new and useful Improvements in Ball-Cocks, of which the following is a specification.

My invention relates to improvements in 10 ball cocks for flush tanks in which the inlet is controlled by ball-float or other suitable means and has for its object generally to reduce the velocity of the water after leaving the feed or supply pipe, thereby 15 eliminating the usual noise incident to the flushing operation, particularly where a high pressure water supply is utilized.

With the above general objects in view, the invention may be defined further as consisting of the combinations of elements embodied in the claim hereto annexed and illustrated in the drawings forming a part hereof wherein—

Figure 1 is a side elevation of the invention partly in section. Fig. 2 is a horizontal section taken on the line 2—2 Fig. 1.

Referring more specifically to the drawings in which like reference numerals designate corresponding parts in each of the 30 views 1 represents the bottom of a flush tank of usual construction apertured as at 2 to receive a flange supply pipe 3 having its outer end connected with a suitable source of water supply (not shown), and 35 the inner end thereof secured to the lower end of a water feed pipe 4.

A truncated cone shaped valve seat member 5 screwed upon the upper end of the pipe 4 is provided with a central opening 40 6 coincident with the bore of pipe 4. This opening 6 is normally closed by a cylindrical valve 7 seating upon the edge 8 of the wall 9 surrounding said opening 6. The valve 7 has the upper portion thereof closely 45 embraced by the contracted upper end 10 of casing 11, which in turn is secured to the outer annular wall 12 of the truncated cone shaped member 5 as by screw threaded connection 13.

50 As best shown in Fig. 1, the casing 11 has an enlarged or bulged portion 14 extending both above and below the valve seat 8 forming an expansion chamber 15 for a purpose about to be described.

55 The inner face of the lower end of the

member 5 is provided with a screw threaded portion 16 adapted to receive the upper end of a correspondingly threaded tube 17 surrounding and concentrically located with respect to the feed tube 4. The tube 17 terminates at its lower end a short distance above the bottom 1 of the flush tank, and at its upper end communicates with the expansion chamber 15 through arc-shaped peripheral openings or slots 18 formed in the member 5.

Any suitable mechanism may be employed for operating the valve 7, but in accordance with the present embodiment of my invention the casing 15 is formed with oppositely disposed upwardly curved arms 19 and 20. The arms 19 and 20 are forked and the former arm projects considerably above the latter. A lever 21 is pivoted at one end between the forks of the arms 20 and has its other end projecting through the forks of the arm 19 and its intermediate portion projecting through the upper looped end 22 of the valve 7. A float lever 23 is pivoted intermediate its ends to the arm 19 and is connected to the end of lever 21 by means of a link 24. It is of course understood that the long end 25, of the float lever carries a float (not shown).

With the parts in the position seen in Fig. 1, the lowering of the end 25 of the float lever 23 causes the valve 7 to rise from its seat. As the valve opens, water rushes from the feed pipe 4 through opening 6 formed in member 5 into the chamber 15, where the force of the water is more or less dissipated, and from this chamber passes out through the openings 18 down the walls of tube 17 finally discharging into the flush tank. By virtue of the fact that the diameter of the tube 17 is considerably greater than the diameter of the feed pipe 4, the water flowing down through the tube is spread over a comparatively large area and consequently the operation of the invention is practically a noiseless one. Moreover, it will be noted that the water in the chamber 15 surrounding the valve seat drops back into the tube 17 with a pressure evenly distributed around the seat.

In practice it has been found desirable to make the tube 17 of such a size that the space between the tube and the inclosed feed pipe 4 will be somewhat greater in area than the interior of the feed pipe, but I

do not wish to limit my invention to these particular dimensions.

As many changes could be made in the above construction and many apparently 5 widely different embodiments of my invention, within the scope of the claim, constructed without departing from the spirit or scope thereof, it is intended that all matter contained in the accompanying specification and drawings shall be interpreted as illustrated and not in a limiting sense.

What I claim is.

A supply valve for flushing tanks comprising a coupling adapted to pass through 15 the bottom wall of a tank and be rigidly secured thereto, a stand pipe detachably connected to and supported by said coupling, a cap threadedly engaging the upper extremity of said stand pipe and provided 20 with an opening extending therethrough, the end of the walls forming said opening

forming a valve seat, a second pipe embracing said stand pipe, threadedly engaging the said cap and terminating short of the said coupling, a cylindrical member with outstanding integral arms secured to the outer periphery of said cap and provided with a central opening extending through the top thereof, a cylindrical plunger valve member slidably disposed within said opening and adapted to rest upon and close said cap valve seat, means pivotally secured to said integral arms adapted to actuate said valve member, said cap provided with openings for establishing communication of said 35 second pipe with said cylindrical member.

In testimony whereof I affix my signature in presence of two witnesses.

ALFRED F. MORENCY.
